UNITED STATES PATENT OFFICE.

JOSEPH GOULBOURN AND REGINALD BOYD WOODCOCK, OF LEICESTER, ENGLAND, AS
SIGNORS TO UNITED SHOE MACHINERY CORPORATION, OF PATERSON, NEW JER-
SEY, A CORPORATION OF NEW JERSEY.

SHAPING MECHANISM.

Application filed December 1, 1921, Serial No. 519,131, and in Great Britain December 2, 1920.

This invention relates to shaping mechanism and is herein illustrated as embodied in a machine designed for grinding heel trimming machine blades to a predetermined form.

The blades of heel trimming machines of the type described in the specification of United States Letters Patent No. 543,349, granted July 23, 1895, on application of 10 Oscar L. Noble, are curved both lengthwise and laterally and are held in a cutter head by arcuate tongues on the head engaging corresponding grooves formed at each side of the blades, such tongues being eccentric 15 to the axis of rotation of the head. These blades do not usually vary in longitudinal curvature and the grooves of all the blades are of the same curvature. For different ranges of work, however, the lateral curvature and the width of the blade, or either 20 alone, may vary. It is important in such a machine that the various blades shall be accurately ground to the form of edge desired to secure the proper shaped heel and to 25 secure the desired angle between the ground face and the outer face of each blade. Heretofore, it has been customary to grind these blades to the form desired merely by the presentation of the blades held by the 30 operator to a grinding wheel.

In view of the foregoing an object of the present invention is to provide a machine by the use of which the accurate grinding of blades such as the cutter blades of heel 35 trimming machines may be facilitated.

In accordance with this object, as herein illustrated, a blade holder is mounted to move across the peripheral edge of an abrading element and also to rock toward 40 and from the abrading element, a templet is provided for controlling the rocking movement of the blade holder, and provision is made for adjusting bodily the position of 45 the templet to compensate for reduction in the diameter of the abrading element as it is worn away during the abrading operation.

As another feature of the invention, there is provided improved mechanism for facilitating the insertion and removal of blades into and from a grinding machine. This is accomplished in the illustrated construction by mounting the blade holder in such a man-

ner that a movement of separation between the holder and the abrading tool is permitted 55 at the completion of the grinding operation.

A further feature of the invention consists in the provision of a novel construction for supporting the blades during the abrading 60 operation which comprises pivotally mounting a blade holder in such a manner that the axis of pivot of the blade holder lies at the center of curvature of a supported blade, providing means for swinging the blade 65 holder about its axis to feed a supported blade in the direction of its length, and imparting traversing movement to the blade holder for causing an abrading element to act along the edge of the supported blades. 70

As the grinding wheel wears away, the aspect of the blade holder with relation to the wheel will change in the absence of a correcting means. As another feature of the invention, there is provided improved mechanism 75 for insuring the proper presentation of the blades to the grinding wheel in spite of a reduction in the diameter of the wheel. As shown, a blade holder and a grinding wheel 80 truing tool are provided with mechanism for varying conjointly their operative positions with respect to the grinding wheel whereby the aspect of these members is maintained unchanged as the wheel wears away.

These and other features of the invention 85 will appear from a consideration of the following specification and accompanying drawings in which:

Fig. 1 is an enlarged side elevation of the machine;

Fig. 2 is a view of the machine shown in Fig. 1 in front elevation,

Fig. 3 is a side elevation in section having certain parts broken away the more clearly to show the mounting of the truing tool and 95 work carrier,

Fig. 4 is a longitudinal view in section showing in detail a portion of the mechanism used in reversing the direction of travel of the work carriage,

Fig. 5 is a rear view showing the construction of the truing tool, and

Fig. 6 is a rear perspective view showing parts of the mechanism included in Fig. 1, and more particularly the arrangement of 105 the spacer lever.

In the illustrated embodiment of the invention a base or standard 14 has suitably secured at its upper extremity a bracket 12 formed with a plurality of bearing arms 10, 10 which rotatably support the shaft of a grinding wheel 8. Power is supplied to the machine generally through a belt 15 adapted to be interchangeably engaged with the tight and loose pulleys 16, 18 mounted on a horizontal pulley shaft 20 in the base frame 14. The grinding wheel shaft is driven from the pulley shaft 20 by a means of a belt 24 running over a pulley 22 fixed to shaft 20 and over a pulley 26 fixed to grinding wheel shaft. For the purpose of grinding cutters from a heel trimming machine a second grinding wheel 28 may be mounted on the extremity of the grinding wheel shaft opposite the wheel 8.

The blades to be sharpened are carried by mechanism which traverses the periphery of the grinding wheel 8. This mechanism includes a centrally bored or hollow shaft 30 (Fig. 2) which is slidable in bearing 31, mounted on the frame 14. Fixed in the bore at one end of this shaft is a nut 32 (Figs. 2 and 4) engageable with a worm or screw 34 held against axial displacement by means of bearings 36, 36 formed on a bracket 38 secured to the head 12. Two continuously driven, beveled gears 40, 42 are fixed against endwise movement on a smooth cylindrical extension of the worm or screw but are free to rotate thereon, being driven by a beveled gear 44 (Fig. 1) secured to the upper end of an inclined shaft 46 journaled in a portion of the bracket 38. This shaft 46 is driven through bevel gears 48, 50 from the horizontal shaft 20. To clutch the bevel gears 40, 42 alternately to the worm screw, a double clutch collar 52 is splined to the extension of the worm or screw and is provided with clutch teeth at both sides to engage cooperating teeth formed on the bevel gears. The clutch collar 52 is moved in either direction by a clutch shifting arm 54, one end of which enters a groove in the collar and the other end of which loosely surrounds a cam rod 76 to be referred to later.

From so much of the description as has already been given it will be understood that the bevel gears 40 and 42 are rotated in opposite directions upon the extension of the shaft 34 by means of the gear 44 (Fig. 1). It therefore follows that if the clutch shifting arm 54 is moved either to the right or to the left, as viewed in Fig. 2, causing the clutch collar 52 to engage one or the other of the oppositely rotating gears 40, 42, the worm or screw shaft 66 (upon which the clutch collar is splined) will rotate in unison with either of the gears 40, 42 engaged by the clutch collar. This provision of means to rotate the worm 34 in opposite

directions (Figs. 2 and 4) will, by the aid of the nut 32, effect movement of the hollow shaft 30 to the right or left of the position shown in Fig. 2, thereby causing the shaft to traverse the periphery of the grinding wheel. As will hereinafter be more fully explained, the equipment which holds the blades during the grinding operation is mounted upon the rod 30, so it will be recognized that the rotation of the worm shaft 34 in opposite directions effects not only traverses of the hollow shaft across the grinding element 8 but also traverses of the work carrier, or blade holder, which is mounted upon the shaft 30.

On this blade holding mechanism which is arranged to traverse the grinding wheel, is a pair of stops 60 and 62 (Figs. 2, 3 and 4) which, as will be described, are adjustable in accordance with the widths of the blades to be ground and determine, by their positions, the times at which the direction of traverse shall change. The stops, at the end of each traversing movement, engage a stud 64 (Figs. 2 and 4) which projects radially from a long slide rod 66 which extends loosely through the hollow shaft 30, through the worm 34 and through a bearing extension 68 (Figs. 2 and 6) of the bracket 38. The rod 66 is actuated by the stops when a blade has completed its traverse of the wheel and, through mechanism to be described, slides the clutch collar 52 alternately into engagement with the clutch teeth on the bevel gears 40, 42. Secured to the rod 66 are two collars 70 and 72 (Fig. 6) which cause the actuation of an arm 74 straddling the rod and fixed on a cam rod 76 which rod is slidable in the bearing extension 68 and in lugs on the bracket 38 (Fig. 2). Fixed to the cam rod 76 are two collars 78 and 80, between which and the clutch shifting arm 54 are interposed two coiled springs which are alternately compressed and extended by movement of the rod 76. For holding the clutch collar in engagement with one or the other of the bevel gears 40 or 42, two pawls 86, 88 are pivoted on horizontal pins on lugs of the bracket 38. The pawls have hooked ends which are also beveled for a purpose which will appear. For disengaging the hooked ends of the pawls from the arm 54 alternately, during reciprocation of the mechanism, cam surfaces 90 and 92 are formed on the cam rod 76 and engage cooperating cam surfaces 94, 96 on the pawls. A certain amount of lost motion between the cam surfaces allows endwise movement of the cam rod 76 and a consequent compression of one of the springs 82 or 84 and the extension of the other spring before the cam surfaces engage.

Turning now to the operation of the mechanism for reversing the direction of travel of the blade carrier across the peripheral

face of the grinding wheel, and assuming that the blade holder is moving to the right (Fig. 2) and that the hooked end of the pawl 86 is hooked over the arm 54 to hold the clutch collar in engagement with the bevel gear 40, as soon as the stop 60, which corresponds to the left hand edge of a blade in the holder, engages the stud 64 (and hence moves the rod 66 and cam rod 76 to the right) the spring 82 will be compressed and the spring 84 extended till the cam surface 90 engages its cooperating surface 94 and thereby raises the hooked end of the pawl 86 from behind the clutch shifting arm 54. The compression of the spring 82 thereupon forces the clutch shifting arm 54 to the right till the hook on the pawl 88 engages behind the arm and thereby puts and keeps the clutch collar 52 in engagement with the opposite bevel gear 42 to change the direction of traverse to the left. Movement of the blade holder to the left ultimately causes the stop 62 to engage the stud 64, and the movement of the slide rod 66 and cam rod 76 to the left, trips the pawl 88 in a similar way and causes the pawl 86 again to lock the clutch collar 52 in engagement with the bevel pinion 40, thus causing another traverse of the mechanism to the right. The arm 54 is enabled to lift the hooked pawls by reason of its engagement with the beveled ends of the hooks.

Since the blades are curved longitudinally and lie directly in front of the grinding wheel, it is desirable, when inserting or removing the blades, to have the holder moved away from the grinder. This may be conveniently accomplished by giving the blade holder an extra traversing movement in one direction at the completion of the grinding action. Near one end of the rod 66 is a spacer in the form of a lever having a handle 100 and an upwardly facing fork 98 adapted to embrace the rod 66 and being interposed between the collar 70 and that end of the arm 74 which straddles the rod 66. The spacer lever may be rocked about the axis of the cam rod 76 to depress the fork 98 by means of a cam lever pivoted at 108 to the arm 74 and having on one arm a finger piece 104 and on the other arm a cam surface 106 arranged to engage the upper surface of the spacer. When the spacer fork is depressed, it will be clear that an extra travel of the blade holder to the right is allowed by reason of the fact that the collar 70 must travel an additional distance, equal to the thickness of the spacer, before it engages the arm 74 and actuates the clutch shifting mechanism. Mounting the spacer in this manner permits the work carrier to move free and clear of the main part of the grinding machine preparatory to the removal or insertion of blades.

To insure that the blade traversing mech-

anism will be stopped positively when the carrier has traveled to its full extent of extra traversing movement, the machine is provided with means for placing and holding the clutch member 52 in a neutral position as soon as the carriage has reached its limit of extra traverse. To this end, there is pivoted, at 110 on the bracket 38, a lever having a hook 114 arranged to engage the clutch shifting arm 54 to prevent its movement beyond a central position. The other arm 112 of this lever is reduced at one end and passes through an enlarged opening 118 in the spacer. A spring 116 connected to the bracket and to the arm 112 tends to raise the hook into engagement with the arm 54. This tendency is resisted when the spacer is in its normal raised position by the contact of the arm 112 with the bottom of the opening 118. As soon as the spacer is lowered, however, the movement of the bottom of opening 118 allows the reduced end of the arm 112 to be lowered, and consequently the hook 114 will rise into the path of the arm 54 to prevent its movement beyond a neutral position. Thus the blade traversing mechanism is stopped positively when the extra traverse is completed and the blades are ready for removal. As will be later described, the blade holder is also given an abnormal rocking movement at this time to facilitate removal of the blades.

The blade holder, which is mounted (by means of bearings 121, 123) to slide with the hollow shaft 30 and to rock thereon, comprises a blade holder carriage 120 having upwardly extending arms 122 and 124, to the upper ends of which is pivoted a yoke shaped frame 126 adapted to receive and support the curved blades 128 and 130. The blades are clamped between a central block 132 fixed to the frame 126 and the end clamps 134 and 136, each clamping member having curved tongues or ridges (Fig. 3) adapted to engage in corresponding grooves on the blades. A hand wheel 138 formed on one end of a right and left screw rod 140, 142 may be actuated to cause the end clamps 134 and 136 to approach one another to exert clamping action upon the blades. Since the blades may differ slightly in width, a lost motion connection in the form of a pin and slot is formed between the screw rod and the central block 132. As shown, there is a cut-out portion 144 in the screw rod into which projects a pin 146 on the central block. This cut out portion allows a slight play of the screw rod and end clamps to compensate for the slight differences which may exist in the widths of the blades. For feeding the blades towards the grinding wheel in an arc about their centers of curvature, the blade holder is provided at one end with a toothed segment 148 (Fig. 1) engaged by a screw shaft 150.

150 mounted in bearings in the carriage 120 and having an adjusting hand wheel 152. The centers of curvature of the blades and of the tongues on their clamping members are located at the pivots of the blade holder to insure the angle of presentation of the blade to the grinding wheel will remain constant as the blade is ground or worn down, thereby providing a substantially uniform bevel on the blade edges irrespective of the amount of wear. The end clamps 134 and 136 have arcuate ribs 154 engaging in grooves on the stops 60 and 62 so that the stops will remain in their adjusted position notwithstanding various angular adjustments of the clamps relatively to the frame 126. When the end clamps are moved, the position of the stops 60, 62 are changed longitudinally of the blade holder carriage an amount depending on the width of the blades. Thus the widths of the blades determine the extent of reciprocation of the blade holder.

It has been hereinbefore pointed out that the blade holder is mounted to rock about the shaft 30 and to the end of effecting and controlling this rocking movement the carrier 120 is provided with a downwardly extending arm 160 (Fig. 1). At its lower end, this arm carries a roller or templet follower 162 on a stud 164 which stud extends substantially radially of the grinding wheel 8, the arm 160 being of such length that the follower 162 is spaced substantially the same distance from the shaft 30 as the pivots of the blade holder. A templet 166 having a surface contour corresponding to the shape it is desired to be imparted to the blade or blades to be sharpened has, at one end, a downwardly extending positioning flange 168 (Fig. 2) to engage the side of a table or templet support 172 formed on a normally fixed frame. Dowel pins 170 extending from this table also aid in locating the templet accurately by engagement in corresponding perforations in the templet. The templet is rigidly secured in position by means of a pair of hooked arms 174 tied together by a rod 176 and pivoted to eccentric pins 178 projecting from a shaft 180 journaled in extensions of the table 172. Whenever the hooks are swung up over the templet, they may be drawn downwardly to clamp the templet against the table by means of the handle 182 secured to the shaft 180. To maintain the templet and follower in cooperative engagement with each other during their relative traverse, a spring-pressed plunger 184 located in the arm 160 carries at its lower end a roller 186 riding on a track 188 which is straight throughout the greater portion of its length and parallel to the hollow shaft 30. Near one end of the track, however, it is cut away or inclined, as at 190, 35 to allow an abnormal rocking movement of

the blade holder whenever the latter has made its extra travel to the right, as above described. This permits an extra movement of the blade holder radially away from the wheel as well as axially beyond it to facilitate the removal or insertion of blades. 70

As the grinding wheel wears away, the angular relation of the blade clamping mechanism relatively to the wheel would change were it not for the provision of a compensating device. To this end, and as shown, there is swingingly mounted on the hollow shaft 30 a frame 192, normally fixed, and carrying the templet-supporting table 172. Likewise mounted to swing on the hollow shaft, is a second frame 194 (Figs. 1, 2 and 3) carrying a grinding wheel truing tool 200. The frame 194 is formed near one end with an arcuate plate 196 (Fig. 5) arranged substantially radially with respect to the wheel and engaged by a similarly formed plate 198 which comprises the truing tool holder. The truing tool 200 is mounted on a forked stud extending from the holder 198 and may be traversed across the wheel by sliding the holder along the arcuate plate 196. The truing tool frame 194 and the templet supporting frame 192 are simultaneously adjusted about their common axis by a right and left screw-threaded shaft 202 (Fig. 1) threaded in rockable studs 204, 204 mounted in arms of the frames 192 and 194. The screw is held against endwise movement by a fixed collar 206 interposed between the forks of a plunger 208 slideable in a fixed bearing 210 on the base frame 14. 90

The blades, when introduced between the clamping members 132 and 134, 136, abut at their ends remote from their cutting edges on fixed stops on the blade holder. The construction is such that the blades, however much worn, can be adjusted about their centers of curvature, by means of the segmental rack 148, to bring the blade to the grinding wheel without varying the angle of presentation of the blade to the grinder. The length of the upwardly extending arms 122 and 124 of the blade holder carriage is chosen to be just sufficient to move the mean point of the average blade likely to be met with, in a line so nearly straight and radial of the grinding wheel as to allow of the reduction of the diameter of the wheel by as much as some 40% without materially affecting the angle of presentation of the blade to the grinding wheel. Evidently the variations in the position of the work holder due to the irregular surface contour of the templet will, at different points of the ground face of any blade, vary the angle last mentioned 110 but the same templet will produce invariably the same result on a similar blade however little of the blade remains and however much the grinding wheel is worn within the limit indicated. The distance of the oper- 130

ating point of the truing tool from the axis of the hollow shaft is substantially equal to the distance between the axis of the hollow shaft and the point chosen as the operating point on the grinding wheel for blade grinding, and the arms through which the right and left screw 202 is threaded being equal in length, the following cooperative adjustments between the parts to be mentioned will result. As the grinding wheel is worn away the operative, by means of the hand wheel attached to the rod 202, advances the truing tool 200 towards the grinding wheel a distance equal to the amount worn away. Since the screws carried by the rod 202 are oppositely threaded, rotation of the rod will cause the arms 192, 194 to approach or recede from one another and in the event the truing tool is moved towards the grinding wheel the templet carrying arm 192 will accordingly move away from the fixed pivot 206 a like distance. This movement of the templet away from the grinder allows the arm 160 carrying the roll 162 to swing outwardly and thereby rocks the blade carrier about the rod 30 towards the grinding wheel. Inasmuch as the lengths of the arms 192, 194 are equal, the templet will move outwardly the same distance the truing wheel moves inwardly. Finally since the arm 160 is of such length that the follower 162 is spaced substantially the same distance from the shaft 30 as the pivots of the blade holder, it will be seen that outward movement of the templet permits a like outward movement of the arm 160 and a corresponding inward movement (towards the grinding wheel) of the blade carrier. Adjustment of the truing tool 200 towards or away from the grinding wheel 8 causes a corresponding and equal adjustment of the blade holder towards or away from the grinding wheel.

Having thus described our invention, what we claim as new and desire to secure by Letters Patent of the United States, is:—

1. In an abrading machine, an abrading element, a shaft, a blade holder mounted on said shaft, means to reciprocate the blade holder across the face of the abrading element, means for rocking the blade holder about said shaft towards and away from the abrading element, a truing tool for the abrading element mounted to rock on said shaft, and means for rocking said blade holder and truing tool through substantially equal distances to insure the proper relation of the holder to the abrading element as

the diameter of the abrading element is reduced.

2. In an abrading machine, an abrading element, a blade holder, a truing tool, a frame supporting the truing tool for swinging movement towards the abrading element, a frame supporting the blade holder for swinging movement towards the abrading element, rocking studs carried by the frame, a sliding fork, and a screw threaded in said studs and held against axial movement by said fork for swinging said frames simultaneously with the wear of said abrading element.

3. In an abrading machine, an abrading element, a slideable shaft, a blade holder mounted to rock upon said shaft towards and away from the abrading element and to slide with said shaft in a direction parallel to the axis of the abrading element, a frame mounted upon said shaft for supporting a templet and a roller connected to the blade holder and adapted to cooperate with the templet, means for sliding and rocking the holder, and means for adjusting the templet supporting frame to allow for reduction in the diameter of the abrading element.

4. In an abrading machine, an abrading element, a blade holder mounted to slide and rock relatively to said abrading element, a frame, means for sliding the blade holder, a templet and cooperating follower interposed between said frame and blade holder for causing the holder to rock during its sliding movement, a track on said frame, a spring pressed roller interposed between said blade holder and said track to maintain the templet and follower in contact, and an inclined portion on said track to allow said follower and templet to separate upon abnormal sliding movement of said blade holder.

5. In a machine for grinding curved blades, an abrading tool, a work carriage, arms extending from the carriage, a blade holder pivoted to the arms, the pivotal axis of the blade holder lying at the center of curvature of the blades, means for swinging the blade holder about said axis to feed a blade in the direction of its length towards the abrading tool, and traversing mechanism for causing the abrading tool to act along the edge of the blade.

In testimony whereof we have signed our names to this specification.

JOSEPH GOULDBOURN.

REGINALD BOYD WOODCOCK.
